(57) **CLAIM**

The ornamental design for a wireless broadcaster, as shown and described.

DESCRIPTION

FIG. 1 is a front perspective view of a wireless broadcaster showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The broken lines encircling the enlarged portion of the claimed design seen in FIGS. 9 and 10 and the reference to the enlargements seen in FIGS. 1 and 2 form no part of the claimed design.

1 Claim, 10 Drawing Sheets
